UNITED STATES PATENT OFFICE.

FRANK L. MACSORLEY AND WILLIAM W. MACSORLEY, OF NEW YORK, N. Y.

GRATE.

Application filed February 4, 1925. Serial No. 6,700.

This invention is a grate adapted for use in stoves and furnaces and the object of the invention is to provide a highly efficient grate construction adapted to be built up from a large number of units all of which are substantially the same.

In its preferred practical form, the invention embodies a grate bar preferably of wrought iron and of polygonal cross section. 10 A square bar may be used to advantage. On this bar is adapted to be assembled a plurality of grate units, each of which is in the form of a substantially circular disc, the periphery of which is fluted so as to form the disc with peripheral teeth. The discs are relatively thin and are provided at their centers with holes adapted to fit the grate bar whereby they are adapted to be positioned on the bar in sequence. Each 20 unit is moreover provided with spacing lugs, the purpose of which is to space the units apart to present to the fire a succession of arcuate fluted surfaces with intermediate draught spaces. With each bar is adapted to be associated at least one unit provided with an extending arm adapted to be pivotally connected to the shaker link to which the other bars of the furnace or stove are also connected and with the link is associated 25 appropriate means for moving the link longitudinally for the purpose of oscillating the units which are pivoted to said link. The oscillation of said units serves to oscillate the grate bars and all other units mounted thereon.

With the terminal units of each grate bar cam surfaces are formed integral and on the furnace are formed projections with which these cam surfaces are adapted to operate to the end that when the grate bars are oscillated, the cam surface will coact with the projections to effect longitudinal movement of the units on each bar first in the one direction and then in the other, so 40 that the grate units are not only oscillated back and forth, but are simultaneously longitudinally shifted for the purpose of effecting efficient breaking up of clinker and freeing the fire from ash.

45 A pronounced advantage inherent in this construction is the ease of initial assembly and also the ability to make repairs in a simple, economical and expeditious manner through the replacement of such units as may be broken and without necessitating an

entire new grate construction when any particular element becomes broken.

Features of the invention, other than those specified, will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a perspective fragmental view showing a portion of one grate bar with one shaker unit thereon and a part of the grate bar support which sustains the weight of one end of each grate bar.

Figure 2 is a fragmental section taken on the line 2—2 of Figure 4.

Figure 3 is a fragmental plan of so much of the construction as is shown in Figure 1;

Figure 4 is a side elevation of an assembled grate.

Referring to the drawings, 1 designates a grate bar shown as square. This bar may be supported for oscillation on its longitudinal axis in any suitable manner, but for the purpose of illustration, I have shown it as supported at its opposite ends by a front supporting bar 2 and a rear supporting bar 3. The bar 1 has a fixed trunnion 4 at its rear end which extends through a circular hole in the bar 3 and at its front end a trunnion 5 is screwed into a tapped hole in the corresponding end of the grate bar and extends through a circular hole in the front supporting bar 2. This arrangement expedites assembly and permits of slight adjustment to compensate for variations in various sizes of firepot.

On the bar 1 is adapted to be mounted a plurality of grate units. These units are of substantially the same configuration and are in the form of a plurality of discs. Of these discs the majority are the same, those designated 6 being identical with one another and in the form of circular discs having fluted peripheries and integrally formed spacing lugs 7 extending from one face thereof. The disc 6a is a combined terminal and shaking disc and varies from the discs 6 in that it is provided on its rear face with two cam surfaces 8 adapted to cooperate with projections 9 mounted on the rear supporting bar 3 or in any other suitable fixed

position. The disc 6^a is further provided with an integral depending shaker arm 10.

The front disc 6^b is of substantially the same construction as the disc 6 except that 5 the spacing lugs are omitted and in lieu thereof two cam members 11 are formed on the forward face of this disc and are adapted for cooperation with projections 12 corresponding in function to the projections 9 10 and supported on the front supporting bar 2 or in any other suitable fixed position.

In making the assembly the units are grouped on the grate bar as shown so as to extend for substantially the full length of 15 the bar with the bar passing through the central holes 14 in each disc. It will be noted from Figure 2 that these holes are, generally, square, but that in each flat side of the square configuration a semi-circular 20 cut out 15 is formed. The purpose of this configuration is to facilitate fitting on the bar and eliminating unnecessary cutting in the event that a slight alteration may be 25 found necessary when placing the discs on the bar. The semi circular cut outs 15 minimize the filing to obtain the desired fit and greatly expedite the work when the discs are formed of rough castings as they generally are in practice.

It will be noted from Figure 4 that when the parts are assembled on the bar and properly spaced apart by the spacing lugs 7 that the cam members 11 on the unit 6^b 30 are placed at 90 degrees to the cam members 8 on the unit 6^a and a sufficient number of the units are placed on the bar, so that when the bar is oscillated in one direction, the cam members 11 will bear against the projections 12 to force all of the units longitudinally of the grate bar in the direction of the projection 9. When the bar is oscillated in the opposite direction the cam members 8 will engage with the projections 9 and force all the units in the opposite 40 direction so that as the bar is oscillated the grate units will be simultaneously shifted back and forth on the bar.

In a furnace installation, it is the practice to employ a number of grate bar assemblies such as are shown in Figure 4 and the stove shaking units 6^a of the respective bars are then connected together by a shaking link 16 to which the arms 10 are pivotally secured. The arms 10 are perforated and studs 16^a, carried by the links, extend loosely through these perforations to permit of sufficient lost motion to insure freedom of movement of the parts. The link 16 is connected with a suitable shaker 17, to impart longitudinal movement to the link 16, and through this movement to effect oscillation of the respective grate bars and the units mounted thereon. In such an assembly, the cam numbers of the units 6^a and 6^b 55

of adjacent bars are preferably set at 90° to one another so that as adjacent bars are oscillated, the grate units on these bars will move in directions longitudinally of the respective bars so as to produce a pronounced 70 grounding action on clinker which may have accumulated on the grate the studs 16^a are long enough to allow of this movement. By this operation the clinker will not only be broken up by longitudinal movement of 75 the grate units of adjacent grate bars in opposite directions, but at the same time there will be a pronounced grounding action due to the oscillation of said units which in practice has been found to pulverize the 80 clinker without appreciable power being required in the shaking operation. By spacing the elements apart on the respective grate bars proper provision is made for the circulation of air through the grate to produce the desired draught and such circulation of air will preclude overheating and consequent warping of the grate units.

From a practical standpoint, the grate of this invention embodies many features of 90 practical importance. In the first place, it will be apparent to those skilled in the art that the elements may be made in the form of rough castings and thus are produced very economically. While the grate bars 95 may be made from castings, they are in practice preferably made of a standard size wrought iron which enables them to be readily drilled and tapped for the trunnions and also allows the standard stock material to be 100 cut off at any desired length for particular grate installations thereby rendering it unnecessary to carry a large assortment of sizes in stock. In making any installation, it is only necessary to cut the grate bars 105 to the proper length and then assemble an appropriate number of elements on the bars. This renders the assembly very simple and economical since skilled help is not required. 110 In the event that the breakage occurs the particular bar effected may be readily removed and the broken part replaced. For example, if one of the discs becomes broken, it may be replaced at the cost of a few cents 115 in material and but little time in labor. This is an important consideration as it does not require that a furnace be shut down until an entire new casting can be obtained as is now the case and then parts of the furnace will not have to be dismantled to make 120 the repair.

Having thus fully described the invention, what we claim as new and desire to secure by Letters Patent is:

1. Grate construction embodying a polygonal grate bar, a plurality of grate units, each of which is assembled on said bar and each of which is provided with a polygonal opening interfitting with the bar, projec- 130

- tions on each unit for spacing them consecutively apart, cam surfaces on the end units, cooperating fixed projections associated with the firebox, and means for oscillating the assembled grate bar and units to effect cooperation between the cam members and the fixed projections whereby oscillation of the assembly will effect a longitudinal shifting of the units on the bar.
- 5 2. Grate construction embodying parallel grate bars of polygonal cross section mounted in spaced relation for oscillation on fixed axes, a plurality of grate elements assembled on each bar and each of which elements is
- 10 15 in the form of a disc having a fluted periphery and spacing projections to space the discs consecutively apart longitudinally of the respective grate bars, each disc being further provided at its center with a hole
- 20 loosely fitting over the bar to lock the disc for oscillation with the bar but to permit longitudinal movement of the disc on the bar, at least one disc of each bar being provided with a radial projection, and a link connecting the radial projections of said
- 25 discs and through which link force may be applied to effect simultaneous shaking of all of the bars and associated discs, in combination with cam members associated with the
- 30 end discs of each bar and fixed projections
- mounted in the path of rotation of said members, whereby oscillation of the bars will effect cooperation between the cam members and the fixed projections and cause longitudinal movement of the grate units 35 on the respective grate bars.
3. A demountable grate unit embodying a substantially circular disc, the periphery of which is fluted and the center of which is provided with a polygonal hole adapted to 40 fit a correspondingly shaped grate bar, and one face of the disc being provided with integral spacing projections, and the other face of the disc being provided with a cam like projection.
4. A demountable grate unit embodying a substantially circular disc, the circumference of which is fluted and one face of which is provided with laterally extending integral spacing projections, said disc being provided at its center with a polygonal hole, the flat sides of which are cut away for a portion of their extent intermediate the angles of the hole to facilitate the fitting of the hole to a polygonal grate bar. 45

In testimony whereof we have signed the foregoing specification.

FRANK L. MACSORLEY.
